PORTABLE LANTERN

Gus G. Potekin, Chicago, Ill., assignor to
Richberry Electric Co., a partnership

Application December 22, 1950, Serial No. 13,547

Term of patent 14 years

(Cl. D48—24)

To all whom it may concern:

Be it known that I, Gus G. Potekin, a citizen of the United States, residing at Chicago, county of Cook, and State of Illinois, have invented a new, original, and ornamental Design for a Portable Lantern, of which the following is a specification, reference being had to the accompanying drawing, forming part thereof.

Figure 1 is an elevational view of one side of a portable lantern, showing my new design;

Fig. 2 is a similar view showing the opposite side thereof;

Figs. 3 and 4 are elevational views of the front and rear ends respectively of the lantern; and

Figs. 5 and 6 are top and bottom plan views respectively of the lantern.

I claim:

The ornamental design for a portable lantern, as shown.

GUS G. POTEKIN.
